Primary Examiner — Holly Baynham*Assistant Examiner* — Rhea Shields(74) *Attorney, Agent, or Firm* — Robert P. Smith(57) **CLAIM**

The ornamental design for a medical console, as shown and described.

DESCRIPTION

FIG. 1 is a front perspective view of the medical console;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The article is not limited to the scale shown herein.

In the drawings, the broken lines are for the purpose of illustrating environment only and form no part of the claimed design.
